UNITED STATES PATENT OFFICE.

WILLIAM F. WEMHOENER, OF ST. LOUIS, MISSOURI.

MAIL BOX.

Application filed April 24, 1926. Serial No. 104,350.

My invention relates to mail receptacles adapted to be built into the wall of a house whereby mail may be deposited in the receptacle from the exterior of the wall and may be removed from the receptacle by a person inside the house. Preferably I desire that mail may be inserted in the receptacle from the inside of the wall also, and may be removed by a person on the outside of the wall.

5 The main object of my invention is to provide a structure particularly adapted for the above mentioned purposes.

It is desirable in connection with such devices to provide face plates surrounding the 15 openings in the building walls and it is an additional object of my invention to provide such face plates and to provide for their mounting in such a way that it will be unnecessary to provide any particular elements in 20 the wall structure to which the face plates may be attached or, indeed, to avoid attaching the face plates to the wall at all.

In the accompanying drawings which illustrate a selected embodiment of my invention:

Figure 1 is a vertical section through the wall of a house having my improved receptacle mounted therein.

Figure 2 is a section taken on the line 30 2-2 of Figure 1 but showing only half of the structure, it being understood that the other half will be a duplicate of that illustrated.

Figure 3 is an elevation of the inner face 35 plate.

Figure 4 is an elevation of the outer face plate and the receptacle.

Figure 5 is a detail of a portion of the receptacle structure as it first appears when 40 applied to the wall.

The body of my device comprises a sheet metal longitudinal box 1, set on end and having openings at 2, 3, and 4. The opening 2 faces the exterior of the wall and it is 45 through this opening that the incoming mail is received and outgoing mail is delivered. The opening 4 is at the bottom of the box and faces the interior of the wall and it is through this opening that incoming mail is 50 removed from the receptacle. This opening is preferably covered by a door 5 hinged to a piece of trim T which forms a finish for the wall opening.

Each of the side walls 6 of the box mounts 55 a bracket 7 which forms a sliding bearing for a bar 8, having its ends turned inwardly

as indicated at 9 and 10, and provided with openings for screws 11 and 12, respectively.

A suitable exterior face plate 13 is mounted on the outer ends 9 of bars 8 by means of 60 bushings 14 and screws 11 and an interior face plate 15 is secured to the inner ends 10 of bars 8 by the screws 12 which are threaded into the inner ends of the sliding bars. By removing screws 11 and 12 the face plates 65 13 and 15 may be disassembled from the box and the box built into the wall of a house without the face plates, which may be applied after all plastering, painting and other work has been completed. The face plates 70 13 and 15 may be then applied and by tightening screws 12 the two face plates will be drawn between each other gripping the wall faces tightly so as to draw the edges of the face plates into contact with the wall surfaces and present a 75 neat and workmanlike appearance. The face plates, however, will be supported by the brackets 7 and will not rely upon their frictional engagement with the wall surfaces to prevent movement along the wall.

In connection with my improved receptacle I utilize the mail receiving structure disclosed in Patent No. 1,477,615, issued to me December 18, 1923, by which the tilting of the mail flap 16 about its pivot 17 causes 80 the letter L, or like matter which has been inserted between roller 18 and member 19, to be projected through the upper part of the flap opening. The inner face plate 15 is provided with an inwardly extending chute 85 20 adapted to partially support outgoing mail matter which is inserted between elements 18 and 19 of the projecting mechanism.

Preferably the lower portion of the outer face plate mounts a bell button 21 from which 90 wiring 22 extends through the wall and around the box to a bell or buzzer within the house.

An incidental feature of my invention is the forming of the flange 23 on the upper end 100 of plate 24. The ends of flange 23 being unconnected to the sides 6 and free to be bent over the upper edge 25 of the outer wall, irrespective of any irregularities of openings in the wall due to rough cutting out of the 105 same.

In my drawings I illustrate a building having an inner and an outer wall between which may mail box is mounted. It is to be understood that the box may be inserted in 110 a brick or tile wall also or in a wall of any other desired construction without eliminat-

ing any of the advantages referred to and, in my claims, references to interior and exterior walls is not to be understood as necessarily meaning separate walls such as indicated in the drawings, but rather to refer to interior and exterior wall surfaces.

I contemplate the exclusive use of all such modifications of the details of my invention as may be suggested in its commercial development so long as the gist of my invention as expressed in the claims is retained.

I claim:

- 15 1. In combination with a mail box adapted to be built into a wall, a face plate for the exterior wall, a face plate for the interior wall, and means mounted on said box for drawing said face plates towards each other and gripping said walls between them.
- 20 2. In combination with a mail box adapted to be built into a wall, a face plate for the exterior wall, a face plate for the interior wall, and means mounted on said box for drawing said face plates towards each other, independently of movement of the body of the box, and gripping said walls between them.
- 25 3. In combination with a mail box adapted to be built into a wall, a face plate for the exterior wall, an element secured to said plate and extending into the box, a face plate for the interior wall, and a member thereon adapted to be adjustably engaged with said element for securing said face plates in position.
- 30 4. In combination with a mail box adapted to be built into a wall, a face plate for the exterior wall, an element secured to said plate and extending into the box, and slidably mounted on the side wall of the latter, a face plate for the exterior wall, and a member thereon adapted to be adjustably engaged with said element.
- 35 5. In a mail box adapted to be built into a wall, an opening for incoming mail, a receptacle for such mail below said opening,

an opening for outgoing mail, a face plate for the interior wall surface adjustable relatively to said box, and a chute mounted on said face plate and projecting into said box to support outgoing mail above said receptacle.

50 6. In a mail box adapted to be built into a wall, an opening for receiving incoming mail, a receptacle for such mail below said opening, an opening for receiving outgoing mail, a face plate for the interior wall surface adjustable relatively to said box, and a chute secured to said face plate and projecting into and slidably mounted on the 55 interior of said box and adapted to support outgoing mail above said receptacle and adjacent to the front of the box.

65 7. In a mail box adapted to be built into the wall of a house, face plates on opposite sides of the box adjustably assembled with each other there being an opening in one of said plates for incoming and outgoing mail, a receptacle for incoming mail below the level of said opening, there being an 70 opening in the other of said plates of said box for outgoing mail, and means for holding outgoing mail adjacent to said first mentioned opening.

75 8. In a mail box adapted to be built into the wall of a house, face plates on opposite sides of the box adjustably assembled with each other there being an opening in one of said plates for incoming and outgoing mail, a receptacle for incoming mail below the 80 level of said opening, there being an opening in the other of said face plates for outgoing mail, and means for holding outgoing mail adjacent to said first mentioned opening, and means for projecting outgoing mail 85 so held outwardly through said first mentioned opening when incoming mail is inserted therethrough.

In testimony whereof I hereunto affix my signature this 22nd day of April, 1926.

WILLIAM F. WEMHOENER.
